[57] CLAIM

The ornamental design for a combined straddle seat and arm rest, substantially as shown and described.

DESCRIPTION

FIG. 1 is a frontal perspective view of a combined straddle seat and arm rest showing our new design;

FIG. 2 is a top plan view thereof;

FIG. 3 is a frontal elevational view thereof;

FIG. 4 is an elevational view thereof taken from the right of FIG. 3, the opposite side being a mirror image thereof; and

FIG. 5 is a rear elevational view thereof.
